UNITED STATES PATENT OFFICE.

JAMES W. FORD, OF CHICAGO, ILLINOIS.

COLLAPSIBLE TOOTHBRUSH.

Application filed May 24, 1922. Serial No. 583,193.

To all whom it may concern:

Be it known that I, JAMES W. FORD, a citizen of the United States, residing at Chicago, in the county of Cook and State of Illinois, have invented certain new and useful Improvements in Collapsible Toothbrushes, of which the following is a specification.

The present invention relates to brushing devices, being particularly concerned with the provision of an improved toothbrush.

The main and primary object of the invention resides in the provision of a collapsible toothbrush characterized by a brush head which may be readily removed from the handle portion and spread longitudinally thereof to form with the same a compact substantially flat assembly for convenient insertion in a suitably shaped pocket case.

While the foregoing statement is indicative, in a general way, of the nature of the invention, other objects and advantages not herein specifically referred to will be appreciated upon a full comprehension of the novel features presented in the construction, arrangement and operation of the present toothbrush structure.

In order that the invention may be readily understood, an exemplifying embodiment of the same is set forth in the accompanying drawing and in the following detailed description based thereon. Obviously, the invention is susceptible of embodiment in other and varied constructional forms without departure from the essence of the invention or the sacrifice of its material advantages; wherefore it is to be understood that the drawing and description are to be taken in an illustrative and not in an unnecessarily limiting sense.

In the drawing

Fig. 1 is a side elevation of the toothbrush, showing the near side of the brush head cover broken away;

Fig. 2 is a top plan view thereof with the brush head cover removed;

Fig. 3 is a transverse section on the line 3—3 of Fig. 1;

Fig. 4 is a transverse section on the line 4—4 of Fig. 2;

Fig. 5 is a side elevation of the toothbrush collapsed and arranged for insertion in a pocket case;

Fig. 6 is a side elevation of the brush head

collapsed with its brush units spread out in end to end relation; and

Fig. 7 is a detail section on the line 7—7 of Fig. 6, showing the nature of the coupling between two adjacent brush unit ends. 60

Referring now with more detail to the drawings, it will be observed that the toothbrush of this invention comprises, in general, a handle portion 10, a brush head 11, and means 12 for effecting a rigid connection between the handle portion and the brush head when the same are properly assembled for use.

The handle portion 10 is formed preferably as an elongated rectangular wire frame 70 characterized by integrally associated pairs of side and end rods 13 and 14, respectively.

The brush head 11 is of a collapsible nature and consists of a plurality of narrow brush units 15 coupled together at their adjacent ends by means of small links 16 hooked about pintles carried in recesses in the ends of the bristle-retaining backs 17 of the units. These units—three of which are preferably employed—may be spread out end to end for convenient packaging with the handle portion or may be folded together by swinging the end units back against opposite sides of the middle unit to form a properly dimensioned composite brush head for assembly with the handle portion. The ends of the bristle-retaining backs 17 are shaped to provide, when the units are assembled in lateral parallel contiguity, transverse grooves across the ends of the brush head. 90

When the units 15 are assembled as described, the resulting composite brush head is inserted in the wire frame with its bristle-retaining back positioned snugly between the side rods 13 of the wire frame adjacent one end thereof. The groove in one end of the brush head receives the transversely disposed end rod 14 against which the brush head is pressed longitudinally of the frame by the hereinbefore mentioned securing 100 means 12.

The means 12 for effecting a rigid connection between the handle portion and the brush head when the same are properly assembled for use consists of a cross-head 18 which is mounted for movement longitudinally of the frame on the spaced side rods 13 thereof which serve as cross-head guides. The bearing element of the cross-head is formed as a transverse rod 19 which is re- 110

ceived within the groove in that end of the brush head opposite to the end of the same cooperating with the end rod 14 of the frame. The cross-head is moved towards or 5 away from the brush head along the side rods 14 by means of a knurled operating rod 20 which is contained substantially in the contour of the frame and is journalled but held against axial movement at one of its 10 ends in a bracket 21 carried rigidly by the handle end of the frame. The opposite end of the rod 20 is screw-threaded and is received within a correspondingly screw-threaded sleeve 22 carried rigidly by the 15 cross-head.

It will be appreciated from this construction that a turning of the operating rod 20 will move the cross-head 18 into or out of securing engagement with the back of the 20 brush head 11, whereby the component parts of the toothbrush may either be readily assembled to form a light, durable and sanitary toothbrush, or may be arranged in collapsed compact form for convenient packing in a substantially flat pocket case. 25

A cap 23 is preferably secured across the side rods 13 of the wire frame above the brush head 11. This cap not only strengthens materially the wire frame but serves 30 both as a positioning abutment for the brush head when being inserted in the frame, and as a sanitary cover across the composite back of the brush head.

I claim:

35 1. A toothbrush construction comprising an elongated handle member having a fixed abutment thereon, a brush head removably associated with the same, and a screw propelled non-rotatable head-engaging element 40 movable longitudinally of the handle member for clamping the brush head rigidly against the abutment.

2. A toothbrush construction comprising an elongated frame, a brush head removably positioned within the frame adjacent one end thereof, and a screw propelled cross-head mounted on the spaced sides of the frame and movable longitudinally thereof to bear against the brush head for 50 clamping the same against one end of the frame.

3. A toothbrush construction comprising an elongated rectangular wire frame, a brush head removably positioned within the frame adjacent one end thereof, and a screw propelled cross-head mounted on the spaced

parallel sides of the frame and movable longitudinally thereof to bear against the brush head for clamping the same against one end of the frame, the ends of the brush 60 head being grooved to interfit with the bearing surface of the cross-head and with the said end of the frame.

4. A toothbrush construction comprising an elongated rectangular wire frame, a 65 brush head removably positioned within the frame adjacent one end thereof, a cross-head mounted on the spaced parallel sides of the frame and movable longitudinally thereof to bear against the brush head for clamping the same against one end of the frame, and means disposed substantially within the 70 contour of the frame for moving the cross-head longitudinally of the frame, said means consisting of a knurled rod journalled at one of its ends in a portion of the frame and threaded at its other end to engage within a correspondingly threaded sleeve carried rigidly by the cross-head.

5. A toothbrush construction comprising 75 a handle member, a collapsible brush head removably associated with the same and comprising a plurality of narrow brush units hinged together at their ends and assembled in lateral parallel contiguity, and means for effecting between the brush units and the handle member a rigid connection.

6. A toothbrush construction comprising 80 a handle member, a collapsible brush head removably associated with the same and comprising a plurality of narrow brush units assembled in lateral parallel contiguity, means for preventing lateral disassociation of the brush units when assembled with the handle member, means bearing against the brush units longitudinally thereof for effecting between the same and the handle member a rigid connection, and a cover carried by the handle member and 85 spanning the backs of the brush units. 90

7. A brush head of the class described, comprising a plurality of narrow brush units hinged together at their ends and adapted for arrangement in lateral parallel contiguity, each unit being adapted for direct interlocking engagement at one end with a mounting frame and at the other end with 95 securing means.

In testimony whereof I have hereunto signed my name.

JAMES W. FORD.
